UNITED STATES PATENT OFFICE.

LAWRENCE F. SMITH, OF HAZARD, KENTUCKY, ASSIGNOR OF ONE-HALF TO WILLIAM B. DE COURSEY, OF HAZARD, KENTUCKY.

RERAILER.

Application filed August 20, 1925. Serial No. 51,437.

To all whom it may concern:

Be it known that I, LAWRENCE F. SMITH, a citizen of the United States, residing at Hazard, in the county of Perry and State of Kentucky, have invented a new and useful Rerailer, of which the following is a specification.

This invention relates to rerailers one of the objects of the invention being to provide novel means for transferring the weight of the car being railed, from the rerailer, throughout the length of the rail on which the rerailer is positioned.

Another important object of the invention is to provide a rerailer which may be adjusted laterally with respect to the railway rail to the end that the rerailer may be used for rerailing car wheels various distances from the rails.

Another object of the invention is to provide means for causing the wheels of the truck of the car which have not been derailed, to pass over the flange of the rerailer that is positioned over the rail of the track.

A still further object of the invention is the provision of means to anchor the rerailer to a railway tie in a manner to prevent movement of the rerailer while the truck of a car is moving thereover.

With the foregoing and other objects in view which will appear as the description proceeds the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view illustrating rerailers constructed in accordance with the invention.

Figure 2 is a sectional view taken on line 2—2 of Figure 1.

Figure 3 is a side elevational view of a rerailer.

Figure 4 is a sectional view taken on line 4—4 of Figure 1.

Figure 5 is a perspective view of a rerailer as illustrated by Figure 1.

Figure 6 is a perspective view of the re-

railer used on the companion rail of the track.

Figure 7 is a fragmental perspective view of a modified form of rerailer.

Figure 8 is a sectional view through one end of the rerailer as shown by Figure 7.

Referring to the drawings in detail, the rerailer includes a body portion indicated generally by the reference character 5, which body portion is formed with grooves 6 disposed in its upper and lower surfaces, which grooves define supporting surfaces 7 and 8 respectively. The supporting surface 7 of each side of the rerailer is disposed at an oblique angle with respect to the side faces of the rail on which the rerailer is positioned, so that a wheel engaging the inner surface of the body portion will move upwardly thereover, the flange of the wheel engaging the inner surface of the supporting surface 7 to cause the wheel to be directed inwardly towards the rail.

As illustrated by Figure 4 of the drawings, the supporting surface 8 is of a height greater than the height of the supporting surface 7, and has its inner end sloping towards the rail so that the tread of a wheel passing upwardly over the rerailer will automatically pass onto the supporting surface 8 as shown by Figure 4 transferring the weight of the wheel, from the rerailer, to the rail on which the rerailer is positioned.

Formed integral with the rerailer and depending therefrom, when the rerailer is in its active position, are hook members indicated at 9, which hook members have their rail engaging surfaces curved as shown by Figure 5 to permit the rerailer to be moved towards or away from the rail on which it is positioned, to adapt the device for rerailing wheels that are various distances from the rail.

Cooperating with each body portion 5 is a companion section or rerailer indicated at 10, which in use is adapted to be positioned adjacent to the outer surface of the rail as shown by Figure 1 of the drawings.

This rerailer section is also reversible and is formed with hook members 11 that are adapted to be hooked over the rail to secure the rerailer thereto in a manner to prevent movement of the rerailer while a car truck is moving thereover. Formed integral with

the rerailer and disposed at each end thereof is a flange 12 adapted to overlie the tread of the rail to support the rerailer, the hook members 11 being formed integral with the flanges 12.

Forming a part of each flange 12 is an enlargement 14 which has its upper surface curved as shown by Figure 6 of the drawing to the end that when the wheels of a truck which have not been derailed, move towards the rerailer, the wheels will pass upwardly over the enlargement 14 and drop onto the rail eliminating any possibility of the rerailer derailing the wheels which are moving over the tracks.

In the form of the invention as illustrated by Figures 7 and 8 of the drawings, the rerailer is provided with a flange 15 formed integral therewith and a spike 16 formed integral with the flange, the spikes being provided with heads 17 which may be struck with a tool such as a sledge hammer to embed the spikes 16 in a tie to insure against the rerailer moving laterally while in use.

Openings 18 are provided in the body portion of each rerailer affording means whereby the rerailer may be hooked over a suitable supporting hook of a locomotive or the like, to the end that the rerailer may be conveniently carried.

I claim:

1. A rerailer including a body portion, outer and inner supporting surfaces forming a part of the body portion, said outer and inner supporting surfaces adapted to accommodate the tread of a wheel being replaced, the outer flanges being of heights greater than the heights of the inner supporting surfaces, and hook members for securing the body portion to a rail.
2. A rerailer including a body portion, said body portion having grooves defining

lateral supporting surfaces, said supporting surfaces being inclined towards one end of the body portion, and hook members formed integral with the body portion to secure the body portion to a rail.

3. A rerailer including a body portion, outer and inner supporting surfaces arranged in spaced relation, and provided on the body portion, hook members formed integral with the body portion, said hook members having inner curved ends adapted to permit the rerailer to move laterally with respect to the rail supporting it, and said supporting surfaces having inner tapered extremities.

4. A rerailer including a body portion, a laterally extended flange formed integral with the body portion and disposed adjacent to the ends thereof, enlargements formed on the flanges and having curved surfaces to permit a wheel to move thereover, and hook members formed on the flanges to be positioned over a rail.

5. A rerailer including a body portion, a flange extending laterally from each end of the body portion, an enlargement spaced from the body portion and formed integral with each flange, the outer edges of the enlargements being curved, and hook members formed on the opposite sides of the flanges.

6. A rerailer including a body portion, flanges formed at the ends of the body portion, spikes formed integral with the flanges, said spikes adapted to be embedded in a supporting tie to hold the rerailer against movement on a rail, and said spikes having heads to permit the spikes to be driven into a tie.

In testimony that I claim the foregoing as my own, I have hereto affixed my signature.

LAWRENCE F. SMITH.
